UNITED STATES PATENT OFFICE.

NOAH W. HOLT, OF BUFFALO, NEW YORK.

ROLLER-MILL.

SPECIFICATION forming part of Letters Patent No. 310,430, dated January 6, 1885.

Application filed October 23, 1883. (No model.)

To all whom it may concern:

Be it known that I, NOAH W. HOLT, of the city of Buffalo, in the county of Erie and State of New York, have invented new and useful 5 Improvements in Roller-Mills, of which the following is a specification.

This invention relates to an improvement in that class of roller-mills which are employed for the reduction of grain, and more particularly to such roller-mills in which one of the rollers is mounted in movable bearings, so that it can be moved toward or from the other roller in adjusting the working-faces of the rollers for grinding or reducing the material 15 to the desired degree of fineness, and also for separating the rollers when the feed is shut off.

The object of this invention is to provide means for adjusting the rollers mounted in stationary bearings, so as to render them parallel with the rollers mounted in movable bearings, and to provide means for adjusting the movable bearings of the opposite roller both separately and simultaneously, and to separate the roller mounted in movable bearings 25 from the roller mounted in stationary bearings without disturbing the grinding adjustment.

My invention consists to these ends of the improvements which will be hereinafter fully set forth, and pointed out in the claims.

In the accompanying drawings, consisting of three sheets, Figure 1 is a side elevation of a roller-mill, partly in section, provided with my improvements. Fig. 2 is a top plan view 35 of a roller-mill with the casing inclosing the rollers in section. Fig. 3 is a vertical section on an enlarged scale of one of the stationary roller-bearings. Fig. 4 is a horizontal section in line $x-x$, Fig. 3. Fig. 5 is a vertical longitudinal section of the adjusting devices applied to one of the movable bearings, on an enlarged scale. Fig. 6 is a vertical cross-section in line $x-x$, Fig. 5. Fig. 7 is a horizontal section in line $y-y$, Fig. 6. Fig. 8 is a vertical section in line $z-z$, Fig. 7, looking outwardly.

Like letters of reference refer to like parts in the several figures.

A A' represent two pairs of crushing or grinding rollers of any suitable and well-known construction.

a a' represent the journals of said rollers, and A^2 represents the casing which incloses the rollers.

B B represent the stationary bearings which support the journals a of the rollers A, and 55 C C represent the movable bearings which support the journals a' of the rollers A'.

D represents the supporting-frame, to which the bearings B and C are attached. The stationary bearings B are secured to the frame 60 D in such manner that they can be adjusted to stand in line with the axis of the rollers, thereby preventing binding of the journals in the bearings, and so that they can be adjusted vertically to render the axis of the roller parallel with the axis of the opposing roller. Each 65 of the bearings B is supported by a pivot, d , which is seated in a circular recess, d' , in the under side of the bearing, and in a similar recess in the upper side of the frame D, and 70 which is made vertically adjustable by means of a set-screw, d^2 , which works in a threaded opening in the frame D, and bears against the under side of the pivot or disk d .

E represents a bracket or standard, which 75 is secured to the upper side of the frame D on the inner side of the bearing B, and e represents a horizontal bolt passing through a vertical elongated opening, e' , in the bracket E and tapping into the bearings B, whereby the 80 bearing is secured to the standard E. The bearing B is constructed with a cylindrical bearing-surface, e^2 , made concentric with the axis of the pivot d , and the outer side of the standard E is provided with a corresponding 85 concave bearing-surface, e^3 , so that before the bearing is secured to the standard by the bolt e the bearing can swivel on the pivot d as a center in adjusting itself to the position of the roller-journal a . After the bearings B at both 90 ends of the roller A have been adjusted on their pivots to properly support the journals a , the holes are tapped into the bearings B for the reception of the bolts e , and said bolts are applied and tightened in the bearings B, and 95 the bolts d are tightened by means of jam-nuts d^2 , whereby the bearing is firmly secured in position. Each of the bearings B may be readily adjusted vertically when necessary, in order to render the axis of the roller A parallel 100

with the axis of the roller A'. The bearings C are arranged to slide on the frame D toward and from the bearings B.

c represents horizontal screw-bolts, which engage with their inner threaded ends in threaded openings in the bearings C, and c' represents externally-threaded sleeves, which surround the bolts c, and pass through lugs c' cast on the frame D.

f represents screw-nuts, which work on the external threads of the sleeves c', and f' are spiral springs, which are interposed between the bearings C and the screw-nuts f, and which surround the bolts c and tend to move the bearings C toward the bearings B.

g represents heads, which are formed on the outer ends of the threaded sleeves c', and which are provided on their inner sides with forwardly-projecting noses g'.

G represents hand-wheels, which are firmly secured to the outer ends of the bolts c for turning the same.

H represents bearings hung loosely on the bolts c between the hand-wheels G and the heads g, and h represents a transverse shaft, which is supported with its ends in the bearings H on the same end of the machine, and provided near both ends with a flattened or eccentric portion, h', arranged opposite the noses g' of the heads g, and adapted to bear against the same. The bearings H are provided with sleeves h'', through which the noses g' project inwardly against the flattened or eccentric portions h' of the shaft h.

I represents actuating-levers secured to the shafts h on the same side of the machine, and connected by a rod, i, so that both the levers I are moved simultaneously. Each of the levers I is provided with a sleeve-bearing, J, which is pivoted to the end of the lever, as shown at j, and which supports the adjacent end of the rod i, which passes through said bearing. The outer portion of the bearing is provided with an external screw-thread, upon which works an internally-threaded sleeve, k.

K represents hand-wheels firmly secured to the reduced ends of the rod i, which form shoulders l, between which and the hand-wheels the hubs of the screw-nuts k are confined.

When the parts are in the position represented in Figs. 2, 5, and 7 and in full lines in Fig. 1, the rollers are in their working position. Upon shifting the levers I to the position represented by dotted lines in Fig. 1 the eccentric portions h' of the shafts h bear against the projections g', forcing the bearings H and the hand-wheels G and screw-bolts c outwardly, thereby moving the bearings C away from the bearings B and separating the working-faces of the rollers and compressing the springs f'. This movement is resorted to for the purpose of spreading the rollers when the feed is shut off or the operation of grinding otherwise interrupted. Upon returning the levers I to their former position the bearings C and the rollers A are returned to their

former positions by the pressure of the springs f'. By turning the screw-bolt c each of the movable bearings C can be adjusted independent of the other, if required, to render the 70 rollers parallel with each other. By turning the screw-sleeve k the shaft h is turned, and both bearings C of the same roller are adjusted simultaneously.

In order to avoid longitudinal displacement 75 of the rod i when the screw-sleeve k is turned, the rod is provided with a dog, m, which can be engaged between jaws m', secured to the side of the casing A', before adjusting the screw-sleeve k, and which serves to hold the 80 rod i against longitudinal motion. This adjustment is resorted to for regulating the grinding adjustment of the rollers, and is not disturbed by spreading the rollers.

It will be seen from the foregoing that the 85 bearings of the rollers A can be readily adjusted to place the rollers parallel with each other, that each of the movable rollers can be adjusted independently to further facilitate the arrangement of the working-faces of the 90 rollers in parallel line, and that both movable bearings C of the same roller can be simultaneously adjusted to increase or reduce the distance between the working-faces of the rollers when necessary for altering the grinding, and 95 that both bearings C can be moved outwardly or away from the stationary bearings B in order to separate the rollers when the operation of grinding is required to be interrupted, and 100 which interferes with the grinding adjustment of the rollers.

I claim as my invention—

1. The combination, with the main frame D, of a bearing-box constructed with a convex back, a standard, E, secured to the frame, and 105 provided with a concave face, in which the convex back of the bearing-box is seated, and a vertically-adjustable pivot, which supports the bearing-box on said frame, the convex and concave contact-surfaces of the bearing-box 110 and standard being curved concentric with the axis of said supporting-pivot, whereby said bearing-box can be turned on the supporting-pivot while resting against the supporting-standard, substantially as set forth.

2. The combination, with the movable bearings C, of adjusting-rods c, tubular screws c', provided with projections g', springs f', and screw-nuts f, hand-wheels G, shaft h, provided with eccentrics h', and bearings H, substantially as set forth.

3. In a roller-mill provided with two pairs of rollers, the outer rollers being mounted in movable boxes C, adjusting-devices whereby each movable box can be adjusted independently, shafts h, provided with eccentrics h', and mechanism whereby both movable bearings of the same roller can be adjusted simultaneously to separate the rollers by turning the shafts h, levers I, secured to the shafts h, 120 a rod, i, connecting said levers, and mechanism applied to the ends of said rod, whereby 125 130

each lever can be adjusted to regulate the grinding adjustment, substantially as set forth.

4. The combination, with the levers I I and mechanism whereby the movable boxes can be adjusted independently and simultaneously, of the connecting-rod *i*, mechanism whereby the connecting-rod can be held against longitudinal movement, and mechanism whereby each lever can be adjusted on the connecting-rod, substantially as set forth.

5. The combination, with the levers I and connecting-rod *i*, of pivoted bearings *J*, hand-wheels *K*, and screw-sleeves *l*, substantially as set forth.

6. The combination, with the levers I I, connecting-rod *i*, and means whereby the levers are adjustably connected to the connecting-rod, dog *m*, and fixed jaws *m'*, substantially as set forth. 15

Witness my hand this 15th day of October, 20 1883.

NOAH W. HOLT.
